CLOSURE OPERATOR AND LOCK

William D. Johnston, Waco, Tex., assignor to Wm. Cameron & Company, Inc.

Application January 6, 1940, Serial No. 312,738

10 Claims. (Cl. 292—199)

This invention relates to closure operators and locks, and more particularly to devices of this kind which are especially adapted for use in connection with casement window sash.

5 Many casement window sash structures are provided with operating devices or mechanism usually mounted at the bottom of the window frame and having an arm or other element connected to the bottom of the hinged sash for 10 swinging the latter to open or closed position. The more efficient of such operating devices now available are capable of closing the bottom of the sash tightly and holding it closed, but they do not exert a directly applied closing or holding 15 effort on the top of the sash. Since the sash is somewhat yieldable, such devices cannot be depended upon to close the sash top tightly, and this is particularly so when the sash is warped or sprung.

20 The present invention relates particularly to a supplemental closure operator and lock adapted to close completely and to lock or hold tightly the portion of a sash which is otherwise not completely closed or held tightly. An object of 25 the invention is to provide an improved closure operator and lock of the character stated which is simple in construction and positive in its action, and which occupies a small space as compared to the space occupied by devices heretofore provided for the same or analogous purposes.

An illustrative embodiment of the invention is shown in the accompanying drawing, in which:

30 Figure 1 is an elevation showing a casement window structure equipped with a closer and lock embodying my invention as viewed from the inside of the window;

35 Figure 2 is a fragmentary vertical sectional view taken on the line 2—2 of Figure 1, showing a screen in addition to the parts shown in Figure 1, and drawn on an enlarged scale. In this view the parts are shown in the positions occupied when the sash is closed at the bottom 40 but not tightly closed at the top, the parts thus being shown in the positions occupied prior to the operation of the closing and locking device embodying the invention.

45 Figure 3 is a view similar to Figure 2 but showing the parts in the positions occupied after the operation of the closing and locking device, and with the top of the sash thus closed tightly;

50 Figure 4 is a sectional view of a part of the closing and locking device showing a worm and

worm gear in elevation, and drawn on an enlarged scale;

55 Figure 5 is a section on the line 5—5 of Figure 4; and

Figure 6 is a detailed sectional view showing a frame-mounted hook and supporting bracket.

The drawing shows a fixed frame A and movable sash B hinged to the frame at 1—1, and a closer and lock constructed in accordance with the invention generally designated C.

The frame A is constructed in a conventional manner to include side members 2 and 3, a top 4, and a bottom 5. Strips 2', 3', 4', and 5' secured respectively to the members 2, 3, 4, and 5 form a marginal abutment against which the sash may be closed in a conventional manner.

The movable sash B also is of conventional form, and includes side members 6 and 7, a top member 8, and a bottom member 9.

55 The frame and sash structure is provided with any suitable operating mechanism located at the bottom of the frame adjacent the hinged side of the sash. Such mechanism is shown as including a rotatable member having a squared socket recess 10 for receiving an operating crank or like member. As previously explained, such sash-operating members cannot be depended upon to effect a tight closing of the sash at the top, and particularly at the top corner diagonally opposite the corner at which the bottom operating mechanism is located. In accordance with the present invention, the improved supplemental closer and lock C is located adjacent the corner of the sash diagonally opposite the corner at which the usual sash-operating mechanism 10 is located.

60 The closer and lock C comprises a bracket 11 secured to the side member 6 of the sash, and a hook 12 pivoted as at 13 on the bracket to swing about an axis perpendicular to the plane 40 of the frame member 2'. The hook is of such length as to extend from the sash within the frame opening. A heel 14 on the hook is engageable with the bracket 11 for limiting downward swinging movement of the hook to the 45 position shown in Figure 2.

65 Mounted on the frame part 6 is a gear housing 15 on which is mounted a worm gear 16 rotatable about an axle pin 17 which is parallel to the hook axis 13 when the sash is in closed 50 position. Integrally formed with the gear 16 is a hook 18 which is adapted to move into interlocking engagement with the sash-mounted hook 12 when the gear 16 is rotated in a counter-clockwise direction from the position shown 55

in Figure 2, continued rotation of the gear applying force through the hooks 18 and 12 and the bracket 11 directly to the sash and moving it forcibly and positively to completely closed and locked position.

For operating the worm gear 16, a worm 19 in mesh with the gear is journaled as at 20-20 in the housing 15. The axis of the worm 19 extends substantially parallel to the plane of the frame member 2' on which the housing 15 is mounted, and is formed at its inner ends with a squared recess 21 adapted to receive the stem or shank of an operating crank indicated in dotted lines at 22 in Figure 3.

Preferably, the gear 16 is formed at a point adjacent the hook 18 with a cam 23 adapted to engage the sash member 6 when the gear 16 is rotated in a clockwise direction from the position shown in Figure 3 so as to positively move the sash outwardly to release it.

The closer and lock C is so constructed that it may be adapted readily for use in connection with either right or left side hinged sash. The drawing shows it applied to a casement window 25 with the sash hinged at the right as viewed from the inside. For use with a sash hinged at the left the pin 17 is removed from the housing 15, the gear 16 with the hook 18 thereon is turned over, and the pin 17 put back in place. The worm 19, being provided with squared recesses 21 at both ends, can be operated from inside the window regardless of whether the closer and lock C is mounted at the right or left of the window.

In operation, when the sash is open and it is desired to close it, the bottom operating mechanism indicated at 10 is operated in the usual manner to close the sash as fully as is possible with the aid of the mechanism 10. This normally will bring the bottom of the sash to snugly closed position, but, because of the yielding of the sash or because of a permanent warp, the top of the sash still may be not completely closed. Such a position is shown in Figure 2. In order to close the top of the sash completely, the crank 22 is inserted in the squared socket of the worm 19, and the latter is rotated so as to revolve the worm gear 16 in a counter clockwise direction as viewed in Figure 2. Engagement of the gear hook 18 with the sash-mounted hook 12 and continued rotation of the gear will pull the sash to the tightly closed position shown in Figure 3. When it is desired to open the sash, the worm 19 and gear 16 are rotated in the opposite direction, causing the cam 23 to press outwardly on the upper part of the sash, thus releasing it if it has any tendency to stick. The opening movement of the gear 16 will be sufficient to position the gear hook 18 out of the path of the sash-mounted hook 12, after which the sash may be moved to its fully open position by operating the mechanism 10.

The provision of the hook 18 on a rotatable gear 16 provides for a substantial closure-effecting movement without requiring long, space-consuming elements. The pivoting of the hook 12 on the sash enables the hook to have definite locking engagement with the gear hook 18 while the hook 18 moves upwardly and downwardly incidentally to its arcuate travel. Proper cooperation of the two hooks is assured by provision of the heel 14 which maintains the hook 12 in the path of the gear hook 18 but spaced above and out of engagement with the gear 16.

It will be observed that the closer and lock disclosed herein can be driven positively in two

directions so as to effect either the complete closing of the sash or an initial release thereof to overcome sticking, and the worm and gear driving connections are such as to be self-locking at any position of the gear 16. The parts are so arranged that the mechanism can be mounted within a small space without interfering with the mounting of an inside screen such as is designated at D in Figures 2 and 3, it being necessary only to provide a small hole in the screen frame through which the operating crank 22 may be inserted. As will be clear from a consideration of Figure 4, the teeth on the worm wheel 16 extend throughout only a portion of its periphery. Consequently, the worm wheel is limited in its rotary movement by engagement of the worm threads with the un-toothed portion of the worm wheel periphery. This prevents over travel of the worm wheel 16 sufficient to pull the hook 12 from its mooring.

The structure disclosed for the purposes of illustration embodies the invention in a preferred form, but it will be understood that various changes may be made without departing from the invention as defined in the claims.

I claim:

1. In a closure operator and lock particularly for casement windows and like structures including a frame and closure member movably mounted on the frame, a hook mounted on the closure member; a gear journaled on said frame and being formed with a gear hook rotatable with said gear and engageable with said closure-mounted hook upon rotation of the gear and while said gear hook has a movement component in the direction of closing movement of the closure for drawing said closure to closed and locked position; and means for rotating said gear.

2. In a closure operator and lock particularly for casement windows and like structures including a frame and a closure member hinged to the frame at one side thereof, a hook mounted on the closure member; a gear housing mounted on said frame; a gear journaled on said housing and being formed with a gear hook rotatable with said gear and engageable with said closure-mounted hook upon rotation of the gear and while said gear hook has a movement component in the direction of closing movement of the closure for drawing said closure to closed position; and means for rotating said gear, said gear being adapted to be turned over with respect to said housing to reverse the direction of extent of the gear hook and to thus render the closure operator adapted for selective right or left mounting.

3. In a closure operator and lock particularly for casement windows and like structures including a frame and closure member movably mounted on the frame, a hook mounted on the closure member; a worm gear journaled on said frame and being formed with a gear hook rotatable with said gear and engageable with said closure-mounted hook upon rotation of the gear and while said gear hook has a movement component in the direction of closing movement of the closure for drawing said closure to closed position; and a worm meshing with said gear for rotating the latter, said worm and gear providing a two-way drive which is self-locking at any position of said gear hook.

4. In a closure operator and lock particularly for casement windows and like structures including a frame and closure member movably

- mounted on the frame, a hook mounted on the closure member; a worm gear journaled on said frame and being formed with a gear hook rotatable with said gear and engageable with said closure-mounted hook upon rotation of the gear and while said gear hook has a movement component in the direction of closing movement of the closure for drawing said closure to closed position; and a worm meshing with said gear for rotating the latter, said worm gear being provided with teeth only partially along its periphery and the untoothed portion of the gear periphery at the end of the toothed section of the gear which advances toward said worm during closing-movement-effecting rotation of the gear being engageable with the worm to limit thereby the rotary movement of said gear and prevent over travel thereof sufficient to pull said closure-mounted hook from its mooring on the closure.
5. In a closure operator and lock particularly for casement windows and like structures including a frame and closure member movably mounted on the frame, a hook pivotally mounted on the closure member; a gear journaled on said frame for rotating about an axis parallel to the pivotal axis of said hook and being formed with a gear hook rotatable with said gear and engageable with said closure-mounted hook upon rotation of the gear and while said gear hook has a movement component in the direction of closing movement of the closure for drawing said closure to closed position; and means for rotating said gear.
6. In a closure operator and lock particularly for casement windows and like structures including a frame and closure member movably mounted on the frame, a hook pivotally mounted on the closure member; a worm gear journaled on said frame for rotation about an axis parallel to the pivotal axis of said hook and being formed with a gear hook rotatable with said gear and engageable with said closure-mounted hook upon rotation of the gear and while said gear hook has a movement component in the direction of closing movement of the closure for drawing said closure to closed position; and a worm meshing with said gear for rotating the latter, said worm and gear providing a two-way drive which is self-locking at any position of said gear hook.
7. In a closure operator and lock particularly for casement windows and like structures including a frame and closure member movably mounted on the frame, a hook pivotally mounted on the closure member; and a gear journaled on said frame for rotation about an axis parallel to the pivotal axis of the hook and being formed with a gear hook rotatable with said gear and engageable with said closure-mounted hook upon rotation of the gear and while said gear hook has a movement component in the direction of closing movement of the closure for drawing said closure to closed position, said closure-mounted hook being formed with a heel adapted to limit movement of the engaging portion of the closure-mounted hook to a position in the path of said gear hook but clear of the remainder of the gear.
8. In a closure operator and lock particularly for casement windows and like structures including a frame and closure member movably mounted on the frame, a hook mounted on the closure member; a gear journaled on said frame and being formed with a hook rotatable with said gear and engageable with said closure-mounted hook upon rotation of the gear in one direction for drawing said closure to closed position, said gear also being formed with a cam adjacent said hook and engageable with said closure for releasing it by positively forcing it toward open position when said gear is rotated in the opposite direction; and means for rotating said gear.
9. In a closure operator and lock particularly for casement windows and like structures including a frame and a closure member hinged on the frame, a bracket secured to said closure member adjacent its margin; a hook pivotally mounted on said bracket to move about an axis perpendicular to the plane of the adjacent frame part and extending to within the frame structure when the closure member is in closed position; a gear mounted on said frame part to turn about an axis parallel to said closure-mounted hook axis, said gear having a gear hook integrally formed on its periphery and said gear hook being directly engageable with said closure-mounted hook upon rotation of said gear and while said gear hook has a movement component in the direction of closing movement of the closure for drawing said closure to closed position; and means for rotating said gear.
10. In a closure operator and lock particularly for casement windows and like structures including a frame and a closure member hinged on the frame, a bracket secured to said closure member adjacent its margin; a hook pivotally mounted on said bracket to move about an axis perpendicular to the plane of the adjacent frame part and extending to within the frame structure when the closure member is in closed position; a worm gear mounted on said frame part to turn about an axis parallel to said closure-mounted hook axis, said gear having a gear hook integrally formed on its periphery and said gear hook being directly engageable with said closure-mounted hook upon rotation of said gear and while said gear hook has a movement component in the direction of closing movement of the closure for drawing said closure to closed position; and a worm meshing with said worm gear and being rotatable about an axis parallel to the plane of said frame part, said worm being formed to receive an operating stem member coaxial with said worm.

WILLIAM D. JOHNSTON.
